UNITED STATES PATENT OFFICE.

CHARLES McKEEVER, OF JERSEY CITY, NEW JERSEY.

VEHICLE-HEADLIGHT.

1,251,457.

Specification of Letters Patent. Patented Dec. 25, 1917.

Application filed January 30, 1917. Serial No. 145,382.

To all whom it may concern:

Be it known that I, CHARLES McKEEVER, a citizen of the United States, residing at Jersey City, in the county of Hudson and State of New Jersey, have invented an Improvement in Vehicle-Headlights, of which the following is the specification.

In my co-pending application, Serial No. 123,616 filed Oct. 4, 1916, I have shown and described an attachment for vehicle lamps in which the lamp bulb is fitted with a cup of transparent or translucent material, with the open end of the cup outermost where the same is provided with a rim carrying a disk through which the pointed tip of the lamp bulb extends. In the use of this device, it has been found that the reflection of the rim, as well as the shadow due to the circular disk produces a double ring effect to which objections have been made by some users. The object of my present invention therefore is to overcome these objections, and in doing so the lamp structure I now prefer to employ preferably comprises a reflector, a bracket or other support secured thereto, and a cup closed at one end and adapted at its open end to be secured in the said bracket in such a position as to surround the lamp bulb in order that the reflected ring as well as the shadow ring to which reference has hereinbefore been made are obviated.

The head light comprising my present invention will be hereinafter more particularly described in conjunction with the accompanying drawing in which Figure 1 is a central transverse section illustrating the invention. Fig. 2 is a front elevation of the bracket support and the cup member secured therein, and Fig. 3 is a rear elevation of the same, Figs. 2 and 3 being made on a materially larger scale than the same parts as illustrated in Fig. 1.

Referring particularly to the drawing the head light made in accordance with this invention preferably comprises a reflector 10 which may be suitably incased in any form of housing. Associated with the reflector is an electric lamp socket 11 fitted with yielding terminals 12 adapted to bear against the contacts in the base lug 13 of an electric

lamp bulb 14. This lamp bulb is secured in position in the socket in any customary manner known in the art.

I also employ a bracket or support 15 which is centrally provided with an opening 16 for the socket 11 and at its periphery is provided with a rim 17 in which there are suitably spaced lugs 18. The bracket is provided furthermore with apertures 23 through 28 which as well as through similar apertures in the reflector 10 rivets or bolts 24 are passed and secured in order to fix the bracket within the reflector.

I also employ a cup member 19 open at one end adjacent which on the outer surface there are spaced screw threads 20 adapted to engage with the corresponding lugs 18 so that when the open end of the cup is inserted in the rim of the bracket and turned a predetermined distance these screw threads engage the lugs 18 to secure the cup in position in the bracket. The main or body portion of the cup 19 is of glass made translucent in any suitable manner, and the outer end of the cup is closed and preferably provided with a cap 21 made integral therewith, the face of which cap may be made more transparent than the remaining portions of the cup. In order to yieldingly maintain the lamp bulb in position, I may employ a felt washer 22 surrounding the base plug of the lamp and lying between the bulb and the base of the bracket.

As will be apparent from the foregoing, the same objects are accomplished by the construction shown and described as those accomplished in the use of the attachment shown and described in my co-pending application aforesaid, namely; the diffusion of the light as reflected from the lamp bulb with no direct vision of the filament of the lamp, and at the same time as hereinbefore stated the possible objectionable features of the reflection of the rim and the shadow from the disk are eliminated.

I claim as my invention:

1. In a vehicle lamp and in combination, a reflector, a bracket permanently secured to said reflector, a lamp bulb, and a cup member surrounding said lamp bulb, and open at one end and closed at the other end and

removably connected and supported at its open end in and by the said bracket.

2. In a vehicle lamp and in combination
a reflector, a socket connected to the re-
flector, a lamp bulb adapted to be received
in the said socket, a bracket securely fixed
to the said reflector, a cup member of trans-

lucent material open at one end and closed
at the other end, and spaced screw threads
adjacent the open end of the said cup and 10
engaging lugs on the said bracket to secure
the cup in a position therein.

Signed this 29th day of January, 1917.
CHARLES McKEEVER.
